UNITED STATES PATENT OFFICE.

CHRISTOPHER DRESSER, OF LONDON, ENGLAND, ASSIGNOR TO JOSEPH WILD & CO., OF NEW YORK CITY.

DESIGN FOR A PRINTED CARPET.

Specification forming part of Design No. 5,330, dated October 31, 1871.

To all whom it may concern:

Be it known that I, CHRISTOPHER DRESSER, of London, in the county of Middlesex, England, have invented a new and original Design for a Printed Carpet, of which the following is a specification:

The nature of my design is fully represented in the accompanying sketch, to which reference is made.

I claim as my invention—

The design for a carpet, as shown.

Witnesses: CHRISTOPHER DRESSER.

THOS. ROUGHT,

ARTHUR HARRIS.
